R. L. Beeler Inventor

By *Lacey, Lacey,* Attorneys

UNITED STATES PATENT OFFICE

RICHARD L. BEELER, OF PADUCAH, KENTUCKY

OCCLUSAL GAUGE

Application filed June 13, 1929. Serial No. 370,639.

The object of this invention is to provide a simple, inexpensive and efficient instrument whereby measurements of a human face may be taken so that the position of the teeth may be accurately determined relative to a fixed point. The invention is designed more particularly for use in dental work and to facilitate the placing of artificial dentures but it may, of course, be used in other fields. The invention is illustrated in the accompanying drawing and will be hereinafter fully set forth.

In the drawings:

Figure 1 is an edge view of a gauge embodying the present invention,

Fig. 2 is a front elevation of the same, and

Fig. 3 is an enlarged detail perspective.

In carrying out my present invention, I provide a frame which is substantially inverted U-shape and formed from a single continuous length of stout wire or light rod. This frame has parallel side portions 1 and an upper arched portion 2 which is offset rearwardly and inwardly, as shown at 3, from the side members 1. The apex of the arch 2 is slightly offset forwardly from the side portions thereof, as shown at 4, whereby the arched extension is adapted to extend across the bridge of the patient's nose and rest comfortably thereon, the side portions of the arch extending downwardly at opposite sides of the nose to points below the eyes. Mounted upon the side members or legs 1 and adapted to move along the same and be held thereto at any desired point are an upper cross bar 5 and a lower similar cross bar 6, these bars being provided at their ends with bearings, as shown at 7, to encircle the members 1 and guide the bars in their movements along the side members. Each said bar is constructed with a central opening through which is slidably fitted an arm 8, the upper surface of which is graduated, as shown at 9, to denote measurements. The legs or side members 1 are each constructed with equally distant spaced notches 10 in their outer surfaces, and these notches may be numbered and graduated to inches and fractions of inches whereby accurate measurements may

be taken. Cooperating with each end of the cross bars 5 and 6 are fastenings in the form of clips 11 having their extremities disposed respectively above and below the adjacent cross bar and formed into hooks or loops 55 adapted to engage notches 10 in the respectively adjacent legs. Retractile springs 12 are attached to the clips and the cross bars and serve to hold the clips in engagement with the notches in which they are set so that 60 the cross bars will be held in the positions to which they are respectively adjusted. The lower arm 8 is formed integral with or rigidly secured to a chin rest 13 which is disposed at the inner side of the frame and has a front 65 upstanding web to which the arm is attached and a lower rearwardly projecting web which is adapted to extend under and bear against the chin of the patient.

The use of the instrument will, it is 70 thought, be readily understood. The frame is set in front of the patient's face with the upper arched extension 2 spanning the bridge of the nose and the offset portions 3 will, consequently, cause the legs or side members 75 1 to assume vertical positions in front of and spaced from the face of the patient. The upper arm 8 is then adjusted so that the rear end of the same will bear against the lower edge of the upper teeth or against the edge 80 of the upper lip and the distance from the apex 4 of the arch to the upper arm 8 is noted upon a chart so that the position of the teeth or the lip relative to the bridge of the nose will be accurately known. The chin rest 13 is 85 adjusted to bear against the chin and the distance of the chin from the bridge of the nose is likewise noted. The graduations or scales upon the arms 8 are also read so as to note the distance between the front of the chin and 90 the vertical plane of the frame and the similar distance from the lip or teeth to the vertical plane of the frame so that the dentist is enabled to prepare an accurate chart indicating the position of the teeth with the 95 mouth closed and the mouth open and, consequently, is enabled to fit artificial dentures without experimental work. The sides of the arched extension 2 are graduated in the same manner that the side 100

members or legs 1 are graduated and the distance of the edge of the lower eyelid from the bridge of the nose may, therefore, be easily noted.

5 My device is exceedingly simple and, therefore, may be produced at a low cost. Owing to the simplicity of its construction, it may be easily manipulated and will give the desired measurements accurately.

10 Obviously the terms "front", "rear" etc. employed in the foregoing description are used in relation to the position of the device when it is in use, the rear side of the frame being the side next to the face of the patient when the device is in place.

15 Having thus described the invention, I claim:

1. An occlusal gauge comprising an inverted U-shaped frame having its side members offset rearwardly at their upper ends and defining an upwardly extending arch to span the nose of a patient with the sides of the frame spaced from the patient and disposed at the sides of the nose, the side members of the frame and the sides of the arch being graduated, measuring elements adjustably mounted upon the sides of the frame, and means for retaining said elements in a set position.

20 2. An occlusal gauge comprising a graduated frame having parallel side members, cross bars slidably fitted at their ends upon the side members of the frame, measuring arms slidably fitted to the cross bars, and means cooperating with the cross bars for maintaining them in set positions upon the side members of the frame.

25 3. An occlusal gauge comprising a frame having parallel graduated side members, cross bars having their ends engaged with the side members of the frame for movement along the same graduated arms slidably fitted to the cross bars, clips associated with the ends of the cross bars to engage the side members of the frame, and means for maintaining the clips in engagement with the side members of the frame.

30 4. An occlusal gauge comprising a frame having parallel graduated side members, cross bars fitted to said side members for movement along the same, graduated arms slidably fitted to said cross bars, clips disposed at the ends of the cross bars and adapted to encircle the side members of the frame, and retractile springs attached to the clips and to the cross bars whereby to maintain the clips in engagement with the side members and hold the cross bars in set positions.

35 60 In testimony whereof I affix my signature.
RICHARD L. BEELER. [L. S.]
